UNITED STATES PATENT OFFICE

EDWARD S. CORNELL, JR., OF WATERTOWN, CONNECTICUT, ASSIGNOR TO THE CHASE COMPANIES, INCORPORATED, OF WATERBURY, CONNECTICUT, A CORPORATION

TUBE-FLANGING TOOL

Application filed February 10, 1931. Serial No. 514,778.

This invention relates to an improvement in tools for flanging the ends of wrought-metal tubes or pipes such as copper water-tubing, etc.

5 The main object of this invention is to provide a simple and convenient tool of the class referred to which while effective for the purpose intended, will avoid, during the flanging operation, the mutilation or distortion of the 10 tube in such manner as would preclude the use of or interfere with the movement of fittings, etc., thereupon.

With the above and other objects in view as will appear from the following, my invention consists in a tube-flanging tool comprising a body-portion; a rigid guide-stem offsetting from the said body-portion for entry into the end of a tube-to-be-flanged; a conical deflecting-surface surrounding the 20 base of the said rigid guide-stem for flaring the end of a tube; and a resilient cushion mounted upon the said guide-stem and engageable with the interior of a tube to cushion the lateral shocks incident to driving the 25 tool into a tube.

My invention further consists in a tube-flanging tool characterized as above and having certain details of construction and combinations of parts as will be hereinafter described and particularly recited in the 30 claims.

In the accompanying drawings:

Fig. 1 is a view in end elevation of a tube-flanging tool constructed in accordance with 35 my invention;

Fig. 2 is a view thereof in side elevation;

Fig. 3 is a view partly in side elevation and partly in longitudinal section;

Fig. 4 is a view corresponding to Fig. 3 40 but showing the tool inserted into the end of a tube-to-be-flanged; and

Fig. 5 is a view partly in side elevation and partly in longitudinal section and showing another form which my improved flanging-tool may assume.

In the embodiment of my invention herein chosen for illustration in Figs. 1 to 4 inclusive, I employ a flanging-tool consisting of a cylindrical body-portion 10 having a driving-face 11 and provided with a rigid axial

guide-stem 12 between the inner end of which and the body-portion proper is formed a conical deflecting-surface 13 outwardly and downwardly flaring from the base of the said stem and terminating in an annular stop-shoulder 14 to limit the flaring action of the 55 tool.

The outer end of the guide-stem 12 is tapered and rounded as shown at 15 and is preferably provided between the tube-deflecting surface 13 and its said rounded terminal 14 with a shallow annular groove 16 into which extends the lower edge 17 of a resilient cushioning-sleeve 18 encircling the said stem and formed of rubber or other equivalent cushioning material. The said resilient sleeve 18 is preferably initially smaller in diameter than the portion of the guide-stem 12 over which it is forced, so as to firmly 60 hug the same.

If desired, the annular groove 16 may be omitted and the resilient cushioning-sleeve 18 extended completely down to the tube-deflecting surface 13 as is shown in Fig. 5. In this figure, also, the body-portion 10 is 65 separately formed from the guide-stem 12 which latter is provided with a base 19 fitting into a recess 20 in the said body-member, which is of cup-shaped form as shown.

In the use of my improved tube-flanging tool, the rigid guide-stem 12 together with its cushion-sleeve 18 is inserted into the end of a tube such as 21 (Fig. 4) and then driven further thereinto by means of hammer or mallet blows delivered upon the driving-face 80 11 of the body-portion, with the effect of causing the tube-deflecting surface 13 to flare the end of the tube as shown in Fig. 4. Now during this driving action, despite the utmost care, the rigid guide-stem 12 will be 85 caused to swing from side to side within the tube due to unavoidably uneven blows, but owing to the presence of the cushion-sleeve 18, the swinging action of the rigid stem is rendered harmless in denting or deforming the tube at its point of contact so that the completed flanged tube will readily permit the sliding action thereupon of the usual couplings or other fittings.

It will be understood by those skilled in 90

the art that my invention may assume varied physical forms without departing from my inventive concept and I, therefore, do not limit myself to the specific embodiment herein chosen for illustration, but only as indicated in the appended claims.

I claim:

1. A tube-flanging tool comprising a body-portion; a rigid guide-stem offsetting from the said body-portion for entry into the end of a tube-to-be-flanged; a conical deflecting-surface surrounding the base of the said rigid guide-stem for flaring the end of a tube; and a resilient cushion mounted upon the said rigid guide-stem and engageable with the interior of a tube to cushion the lateral shocks incident to driving the tool into a tube.

2. A tube-flanging tool comprising a body-portion; a rigid guide-stem offsetting from the said body-portion and provided with a tapered terminal for entry into the end of a tube-to-be-flanged; a conical deflecting-surface surrounding the base of the said rigid guide-stem for flaring the end of a tube; and a resilient cushioning-sleeve encircling the said guide-stem including a portion of the tapered terminal thereof and engageable with the interior of a tube to cushion the lateral shocks incident to driving the tool into the said tube.

3. A tube-flanging tool comprising a body-portion; a rigid guide-stem offsetting from the said body-portion and formed with a tapered terminal for entry into the end of a tube-to-be-flanged; a conical deflecting-surface surrounding the base of the said rigid guide-stem for flaring the end of a tube; and a resilient cushioning-sleeve encircling the said guide-stem for engagement with the interior of a tube to cushion the lateral shocks incident to driving the tool into the said tube; the said cushioning-sleeve extending from and including a portion of the tapered terminal of the said rigid guide-stem to substantially the said conical tube-deflecting surface surrounding the base of the same.

In testimony whereof, I have signed this specification.

EDWARD S. CORNELL, JR.
